UNITED STATES PATENT OFFICE

2,226,002

METHOD AND APPARATUS FOR SIZING AND FINISHING PROJECTILES

Anthony J. Langhammer, Detroit, Mich., assignor to Chrysler Corporation, Highland Park, Mich., a corporation of Delaware

Application October 20, 1938, Serial No. 235,936

2 Claims. (Cl. 29—1.22)

This invention relates to an improved method and apparatus for finishing and sizing projectiles.

More specifically, the invention pertains to an improved method and apparatus of this kind which is particularly adapted for the sizing and finishing of porous metal bullets having a substantial lubricant absorbing capacity and comprising compressed and sintered powdered metal.

One of the main objects of the invention is the provision of a high speed production method and apparatus for sizing and finishing bullets of the foregoing character.

Another object of the invention is the provision of a method and apparatus of this kind by which the body, ojive and both extremities of a projectile shaped blank can be simultaneously brought to desired dimensions and contour within close limits in a single operation which also produces a smooth external surface.

A further object of the invention is the provision of a method and apparatus of this character by which projectile blanks comprising porous metal can be finished and shaped without destroying the porosity and lubricant absorbing and exuding capacity of the interior portions of the resulting product.

An illustrative embodiment of the invention is shown in the accompanying drawing, in which:

Fig. 1 is a side elevational view, partly in section, of a projectile finishing and sizing apparatus embodying the invention and by which the improved finishing and sizing operation may be performed.

Fig. 2 is an enlarged end elevational view showing a pair of die members included in the apparatus arranged in close-fitting and registering relationship.

Fig. 3 is an elevational view, partly in section, of a projectile which has been finished and sized in accordance with the invention.

While the sizing and finishing apparatus illustrated in the drawing is particularly adapted for the finishing and sizing of bullets comprising porous metal formed of compressed and sintered powdered metal, it is apparent that the same may be employed to advantage in the finishing and sizing of projectiles and similar articles formed of diverse other materials. This apparatus includes a frame structure, generally design-

nated by the numeral 10, in which is provided a vertically extending guide way 11. A slide block 12 is reciprocably mounted in the guide way 11 and operatively connected by a link 13 with mechanism by which it is drivingly reciprocated. This driving mechanism comprises a counter-weighted crank arm 14 fixed to a shaft which is journaled at 15 on a bar 16 provided at the upper extremity of the frame structure 10. A pulley 17, non-rotatably fixed to the shaft, is drivingly connected by a belt 18 with a motor 19 mounted on a bracket 20 extending outwardly from the frame structure 10.

Fixed and movable die members 21 and 22 are carried by the slide block 12 and frame structure 10 respectively. The movable die member 22 is disposed in a recess 23 formed in the right lateral edge portions of the slide block 12 which protrudes forwardly, as viewed in Fig. 1, from the frame structure 10, the die member 22 being fixed in position by bolts 24. The die member 21 is adjustably secured to the frame structure 10 by bolts 25 extending through slots 26 formed in the die member. These die members are so constructed and arranged as to have opposed registerable sides 27 and 28 extending in the general direction of travel of the movable die member 22.

Formed in the sides 27 and 28 of the die parts 22 and 21 respectively are longitudinally extending registerable grooves generally designated by the numerals 29 and 30 in Fig. 2. The grooves 29 and 30 are bounded by opposed faces which have a combined profile that corresponds substantially to the contour and dimensions of the longitudinal diametric cross section desired in a finished projectile 31 such, for example, as that shown in Fig. 3. The projectile illustrated in Fig. 3 comprises a substantially cylindrical body 32, an ojive 33 and a base extremity 34. The opposed side faces bounding the grooves of the die members 21 and 22 each comprise relatively flat surface portions 35 which are adapted to contact the body 32 of a projectile blank. The remaining lateral surface portions of the faces bounding the grooves 29 and 30 each comprise converging arcuately concaved surface portions 36 for engaging the ojive 33 of a bullet blank. Provided at the lower extremity of the flat surface portions 35 of the faces bounding the grooves 29 and 30

5490</p

the ojives of the projectiles are brought to an exceedingly smoothed and polished condition by reason of the combined rotative and slipping action to which they are subjected while in contact with the operative faces of the die members.

5 The foregoing finishing apparatus and method is especially suitable for the finishing and sizing of projectiles formed by compressing a mass of thoroughly mixed together, finely divided particles comprising, for example:

	Parts by weight
Powdered copper	90
Powdered tin	10
15 Stearic acid	½
Boric acid	½
Graphite	1½

10 The above mixture may be compressed to a desired projectile shape in a suitable die and then removed from the die and sintered in a non-oxidizing or reducing atmosphere at a temperature of from substantially 1500° F. to 1550° F.

20 After the sintering operation, the resulting projectile blank may be impregnated with liquid lubricant by immersing it while hot in an oil bath. This lubricant impregnating step may either precede or follow the finishing and sizing operation as desired. The compressed and sintered projectile blank which may be slightly over-sized in 25 dimensions may then be subjected to the foregoing sizing and finishing operations by which a substantially smooth exterior surface is obtained while the blank is simultaneously brought to predetermined dimensions.

30 35 Although but one specific embodiment of the invention is herein shown and described, it will be understood that various changes in the size, shape and arrangement of parts may be made without departing from the spirit of the invention.

40 I claim:

1. In apparatus for sizing and surface finishing a projectile having an ojive, a substantially cylindrical base portion and a flat extremity opposite said ojive including a pair of die members having complementary longitudinally extending surface portions corresponding to the contour of and engageable with said ojive, base and extrem-

ity of said projectile respectively, each of said die members having surface portions contacting with said base and constituting the only surface of said dies directly opposing movement of said projectile under the axial thrust applied thereon by 5 compression of said ojive portion means for supporting said die members for relative movement longitudinally of said surfaces from a location beyond one end of one die to a location beyond the opposite end of the latter die, said die members 10 being so constructed and arranged as to accommodate insertion of an over-sized projectile therebetween when in one end to end relation and to bring said over-sized projectile to desired dimensions when in an opposite end to end relation, and means for moving said die members between said positions for rolling peripheral portions of said projectile therebetween and forcefully rubbing the extremity of said projectile on the surfaces of said dies with which it is engaged. 20

2. Apparatus for finishing and sizing a projectile including a frame structure, a slide block shiftably mounted on said frame structure, a die fixed on said frame structure having a side extending along the path of movement of said slide 25 block, a die mounted on said slide block having a side facing said side of said first mentioned slide block and movable with said slide block from a position entirely beyond one extremity of said fixed die to a position entirely beyond the 30 other extremity of the latter die, said facing sides of said dies being provided with longitudinally extending registerable grooves having a combined cross section corresponding to the diametric cross section of said projectile, means for reciprocating said slide block to move the die mounted thereon from a position beyond one end of the fixed die to a position beyond the opposite end thereof, mechanism operable in timed relationship with respect to movement of said block and 35 the die thereon for automatically feeding a projectile to be finished between the surfaces of said grooves each time said movable die is in one of said limiting positions, and means adjacent the other limiting position of said movable die for receiving said projectile each time said movable die is brought to its opposite limiting position. 45
